(57) **CLAIM**

The ornamental design for a pile guide for docks for internal application, as shown and described.

DESCRIPTION

FIG. 1 is a top perspective view of a pile guide for docks for internal application showing the new design;

FIG. 2 is a bottom perspective view of the pile guide for docks for internal application;

FIG. 3 is a top plan view of the pile guide for docks for internal application;

FIG. 4 is a bottom plan view of the pile guide for docks for internal application; and,

FIG. 5 is a front elevation of the pile guide for docks for internal application; the rear elevation, right side and left side of the pile guide for docks for internal application are identical in appearance to the front elevation.
